COMBINATION COMB, HAIR BRUSH AND CONTAINER HOLDER

Stephen W. Harris, Mission Hills, Kans., assignor to L. T.
York Company, Kansas City, Mo., a corporation of Missouri

Filed Oct. 28, 1963, Ser. No. 77,163

Term of patent 14 years

(Cl. D9—2)

Fig.1.

Fig.2.

Fig.3.

Fig.4.

Fig.5.

FIG. 1 is an elevational view of one side of a combination comb, hair brush and container holder, showing my new design;

FIG. 2 is a top plan view thereof;

FIG. 3 is an elevational view of one end thereof;

FIG. 4 is an elevational view of the side opposite to that shown in FIG. 1; and

FIG. 5 is a bottom plan view thereof.

The broken line showing of the container is for illustrative purposes only.

I claim:

The ornamental design for a combination comb, hair brush and container holder, as shown and described.
